UNITED STATES PATENT OFFICE.

WILLIAM H. MUSSEY, OF CHICAGO, ILLINOIS, ASSIGNOR TO PULLMAN CAR AND MANUFACTURING CORPORATION, OF CHICAGO, ILLINOIS, A CORPORATION OF ILLINOIS.

CAR TRUCK.

Application filed July 8, 1926. Serial No. 121,172.

My invention relates to car trucks for use in railway cars generally, and particularly in cars engaged in passenger carrying service.

One object of my invention is to prevent the synchronization of the truck springs and of the springs and car body without disturbing the normal functioning of the springs and without the use of extraneous dampening devices.

10 Another object is to so dispose and proportion the coil springs in the truck organization that the aggregate deflection obtained will be in excess of the maximum compression value of any one of said springs.

15 A further object is to utilize the great stability of coil springs having less working load height than their respective diameters and to dispose the springs thus proportioned to obtain an aggregate deflection in excess of 20 the maximum compression value of the individual springs.

A further and important object is to dispose coil springs of different frequencies respectively above and below the equalizers so 25 that vibrations set up by abrupt changes in the direction and magnitude of the applied stresses will not be synchronized.

Another object is to provide a pivotal mounting for the springs having a bearing 30 upon the equalizing of the truck and adapted for temporary connection with the frame of the truck during the assembling operation.

In carrying out my invention, I provide a truck frame mounted upon coil springs of a 35 given frequency and a pair of underlying equalizer bars supported at their respective ends upon journal box coil springs of another and different frequency, the purpose being to cause the set of springs upon the equalizers 40 to vibrate asynchronously with respect to the springs supporting said equalizers, so that vibrations set up in the springs supporting the equalizer bars will be offset by those occurring in the springs upon the equalizers, 45 thereby preventing the building up of the combined recoil values of the several springs and communicating them to the car body in the form of reactions to truck movement over high spots and depressions in the track. Be- 50 cause of the stability inherent in springs of greater diameter than working load height, their use is preferred since side thrusts caused by sudden changes in the direction and intensity of stresses resulting from buffing im- 55 pact or the surging, swaying and lagging

movements of the car are met by springs thus proportioned without appreciable side sway or eccentric loading of the coils.

The foregoing and other objects are attained by the mechanism illustrated in the 60 accompanying drawings, in which,—

Fig. 1 is a plan view of the truck;

Fig. 2 is a dual view showing a side elevation of one half the truck and a partial sectional view of the other half taken on line 65 2-2 of Fig. 1, and looking in the direction indicated by the arrows, a portion of one of the pair of wheels being broken away to better show the method of mounting the respective equalizers upon the springs resting upon the 70 journal boxes;

Fig. 3 is a vertical sectional view taken on line 3-3 of Fig. 1, looking in the direction indicated by the arrows and showing the method of seating the truck frame upon one 75 of the supporting springs pivotally mounted upon an equalizer bar;

Fig. 4 is a vertical sectional view taken on line 4-4 of Fig. 1, looking in the direction indicated by the arrows and showing the truck 80 frame assembled with the spring, spring cap, and equalizer bar at the truck pedestal position and indicating the opening in the pedestal jaw for the reception of the equalizer bar;

Fig. 5 is a similar view of the truck taken on line 5-5 of Fig. 2, looking in the direction indicated by the arrows and showing the swing bolster hanger mechanism mounted upon the transoms of the truck frame in as- 90 sembled relation with one of the equalizer bars;

Fig. 6 is an isometric underside view of the combined spring cap and equalizer bar seat at the journal box position; and

Fig. 7 is an isometric sectional view of the truck frame supporting spring seat showing its upper side formed with an open pocket to receive the head of a bolt employed to temporarily secure the seat and spring to the truck frame in the process of assembling with the equalizer bar.

In the drawings, 10 represents the frame of the truck comprising the wheel pieces 11 connected intermediate their ends by transverse 105 transoms 12 spaced apart to receive a swing bolster 13 between them. The bolster rests upon elliptic springs 14 seated upon a spring plank 15 having a bearing at its ends upon cross-bars 16 connecting the lower ends of 110

- swing links 17 pivoted at 18 upon the transoms as best shown in Figs. 1, 2, and 5. Spaced above the elliptic springs 14 are equalizer bars 19 supported at their ends upon the journal box springs 20 and depressed between their ends and said springs to provide space between the bar and the wheel piece 11 for the frame supporting springs 21 mounted at intervals upon the equalizer bar at points 5 between the journal box springs. The wheel pieces 11 are fitted at their ends with pedestal jaws 22 flanking the journal boxes 23 and springs 20 and adapted for vertical movement between guides on the journal boxes.
- 10 The wheel pieces are further provided with inwardly projecting bracket portions 25 adjacent the transoms 12 for supporting the brake rigging. The dead levers 26 are pivotally mounted upon the brake heads 27 supported from hanger links 28 suspended from the brackets 25; said brake levers 26 are anchored to guides 29 pivoted to lugs 30 on the brackets. The live brake levers 31 are similarly supported on the opposite side of the 15 bolster 13; the brake heads 32 are hung from hanger links 33 suspended from brackets 25 and connected at their lower ends to the dead levers 26 by compression bars 34 and actuated by means of a brake equalizer bar 35 connecting the live levers at their upper extremities to the air cylinder pull rod 36 at the center of the car, the brake equalizer being slidably supported upon strap brackets 37 secured to adjacent transoms 12 as best 20 shown in Figs. 1, 2, and 5 of the drawings.
- 25 The supporting equalizers 19 are provided with spring seat supporting pins 40 having each a relatively large intermediate portion 41 snugly fitting respective openings in the 30 equalizers and contracted trunnion portions 42 projecting from opposite sides of the equalizers. These pins are designed to carry a bifurcated spring seat 43 astride the equalizers as best shown in Fig. 3 of the drawings 35 to provide a pivotal mounting for the spring seat and permit slight rocking movement thereof in response to the constantly shifting relation between the frame supporting springs 21 and the equalizers 19. The seats 43 are removably mounted upon the trunnions 42 and provided with a pair of downwardly opening bearing portions 44 spaced apart to provide an intermediate opening 45 for the reception of the associated equalizer 19 between them. Rising from the 40 spring bearing portion 46 of the respective seats 43 are bolt head pockets 47 open downwardly and to one side to receive the head of a bolt 38 shown in dotted lines in this figure for temporarily securing said seats 43 with respective springs 21 to the adjacent wheel piece 11 during the assembling of the equalizers 19 with the truck frame; for this operation the bolt 38 is entered 45 through openings 48 in the wheel piece, and

fitted with a relatively large supporting washer 49 covering openings 48 and there held by suitable nuts 39 also indicated in dotted lines.

The truck frame supporting springs 21 are disposed on opposite sides of the transverse center of the truck and intermediate the pedestals and transoms of the truck frame as shown in Figs. 1 and 2 of the drawings; this disposition of the springs 21 permits of the use of a wheel piece of a relatively small cross-sectional area between the spring pockets 50 of the truck frame by virtue of which a substantial reduction in the depth of the wheel pieces 11 may be effected for a purpose that will presently appear. The reduction in the depth of the wheel pieces between the spring pockets 50 permits the dropping of the upper side of this portion of the frame below the upper extremities of the brake levers and their connections and the raising of the underside of said reduced section to provide ready access to the brake gear for inspection and replacement; the dropping of the upper side of the wheel pieces 11 lends itself to the use of equalizer bars 19 having their ends supported upon the journal box spring caps 51 at levels substantially higher than the trunnion supports 42 for the pivoted spring seats 43 in the depressed portion of the equalizers thus further enhancing the stability of the assembled structure and materially lowering the center of gravity of the truck as will be understood. The construction admits of the use of relatively shallow equalizer bars 19 which also permits ready access to and inspection of the swing bolster mechanism from the side of the car since the equalizers are housed within their respective wheel pieces 11 and well above the elliptic springs 14 supporting the bolster 13. As indicated in Figs. 3, 4, and 5 of the drawings, the pedestal jaws 22 and transoms 12 are provided with openings 52 and 53 respectively for the reception of the equalizer bars 19; the bars are assembled with the truck frame by first entering them in openings 52 in one of the pedestals 22 and passing them through the openings 53 in the transoms 12 and finally through openings 52 in the pedestals 22 at the opposite ends of the wheel pieces 11 as best shown in Figs. 1 and 2 of the drawings.

In assembling the equalizers 19 with the truck frame 10, the frame supporting springs 21 and their respective seats 43 are first secured to the wheel pieces 11 by means of the temporary bolt 38 above noted before the equalizers are introduced, since it would be impossible to enter the springs and seats after the bars are in place as will be obvious; after the equalizers are in position with their ends resting upon the journal boxes 23, supporting pins 40 are inserted in suitable openings in the equalizers 19, and journal box

5 springs 20 with their respective cap pieces 51 are then mounted upon the journal boxes and under the ends of the equalizers thereby raising the equalizer bars to effect operative engagement between trunnions 42 of pin 40 and bearings 44 of spring seats 43, whereupon the bolts 38 holding the seats 43 and springs 21 to the frame, are removed. Because of their position between two sets of springs located 10 above and below them, the equalizer bars will transmit the full compression value of the set of springs 21 above said bars 19 to the other spring set whereby the flexibility of the truck as a whole is increased to the extent of the 15 additional compression value of said springs 21. Thus positioned, the equalizer bars 19 become floating members through the medium of which vibrations set up in one set of springs are transmitted to the other to prevent synchronization between them without affecting the 20 normal flexibility of the several springs.

In the arrangement described there has been provided a mechanism designed to absorb the vibrations arising from inequalities 25 in the track structure when traversed by cars of great weight and capacity at high speeds. As designed, the mechanism prevents the transmission of shocks occasioned by the rapid passage of the wheels over high spots and 30 depressions in the rails to the car body, by the use of floating equalizers suspended between springs of different capacities. It should be noted that while springs of different diameters are preferred and shown in the present 35 embodiment, it is conceivable that within the scope of the invention the required difference in the capacities of the springs respectively above and below the equalizers may be obtained with springs otherwise proportioned, 40 and though double coils made up of springs of different capacities are used to obtain a localized dampening effect at the several spring positions the inner coils may be dispensed with if desired, without affecting the 45 operation of the assembly as a whole. It should also be noted that while the invention is described with special reference to four wheel trucks, the invention may be adapted with equal facility to six wheel trucks.

50 What I claim is:—

1. A railway car truck including journal boxes, coil springs having a predetermined frequency value mounted upon said boxes, equalizer bars supported at their ends upon 55 said springs, other coil springs having a frequency value different from said first mentioned springs mounted upon said equalizer bars, and a truck frame supported upon said last mentioned springs, the outer coils of all 60 of said springs being severally of greater diameter than their respective working load height.

65 2. A railway car truck including journal boxes, springs upon said boxes, equalizer bars depressed between said boxes and

supported at their ends upon said springs, other springs pivotally mounted upon said equalizer bars intermediate their ends, and a truck frame supported upon said last mentioned springs, said frame having dropped 70 portions between said pivotally mounted springs and adapted to receive said equalizer bars.

3. In a car truck including journal boxes, 75 springs upon said boxes, equalizer bars depressed between said boxes and supported at their ends upon said springs, other springs upon said equalizer bars intermediate their ends, and a truck frame supported upon said last mentioned springs, said 80 truck frame being adapted to house said springs and equalizers.

4. In a car truck including journal boxes, 85 springs upon said boxes, equalizer bars within said truck frame and depressed between said boxes and supported at their ends upon said springs, frame-supporting springs upon said equalizer bars intermediate their ends, and a truck frame supported upon said 90 springs, said frame having dropped portions between said frame-supporting springs adapted to receive said equalizer bars.

5. In a car truck including journal boxes, 95 truck frame wheel pieces having dropped intermediate portions terminating in spring pockets at relatively higher levels, springs upon said boxes, equalizer bars depressed between said boxes and supported at their ends upon said 100 springs, other springs entered in the pockets of said truck frame wheel pieces, and seats for said last named springs pivotally mounted upon said equalizer bars.

6. In a car truck including journal boxes, 105 wheel pieces having dropped intermediate portions terminating in spring pockets at relatively higher levels, springs upon said boxes, equalizer bars depressed between said boxes and supported at their ends upon said springs, other springs entered in the pockets 110 of said wheel pieces, and seats for said last named springs pivotally mounted upon said equalizer bars and adapted for temporary attachment to said wheel pieces.

7. In a car truck including journal boxes, 115 wheel pieces having dropped intermediate portions terminating in relatively higher spring pockets, springs upon said journal boxes, other springs entered in the pockets of the wheel pieces, and equalizer bars supported between both sets of springs.

8. In a car truck including journal boxes, 120 springs upon said boxes, wheel pieces having dropped intermediate portions terminating in spring pockets at relatively higher levels, springs entered in the pockets of said wheel pieces, and equalizer bars extending below and supporting said last mentioned 125 springs and the wheel pieces, said equalizer bars having raised terminal portions beyond said last mentioned springs adapted for sup-

- port upon the springs at the journal boxes.
9. In a car truck including journal boxes, springs upon said boxes, wheel pieces having dropped intermediate portions terminating in spring pockets at relatively higher levels, equalizer bars supported upon said springs and having depressed portions intermediate said boxes, springs entered in the pockets of said wheel pieces, and seats for said last mentioned springs pivotally mounted upon said equalizer bars and provided with open sockets in their upper faces for the reception of attaching devices for temporarily securing them to the wheel pieces.
10. 10. In a car truck including journal boxes, equalizer bars yieldingly supported upon said boxes, a truck frame yieldingly supported upon said equalizer bars and having pedestals and connecting transverse transoms, and openings in said pedestals and transoms for the passage of said equalizer bars.
11. A railway car truck including journal boxes, a set of coil springs upon said boxes, equalizer bars supported at their ends upon said springs, another set of coil springs upon said equalizer bars intermediate their ends, and a truck frame supported upon said last mentioned springs, the springs of one set having capacities respectively different from those of corresponding springs of the other set, the outer coils of all of said springs being severally of greater diameter than their respective working load height.
12. In a car truck including equalizer bars and springs supported on said bars, seats for said springs pivotally mounted on said bars, and supporting pins for said seats journaled in said bars and held from displacement by said seats.
13. In a car truck including equalizer bars and springs supported on said bars, seats for said springs pivotally mounted on said bars, and supporting pins for said seats journaled in said bars and having intermediate and end
- trunnion portions, said seats having downwardly opening trunnion bearing portions adapted to hold said pins from displacement.
14. A railway car truck including journal boxes, coil springs upon said boxes, equalizer bars supported at their ends upon said springs, other coil springs upon said equalizer bars intermediate their ends, and a truck frame supported upon said last mentioned springs, the outer coils of said springs being severally greater in diameter than their respective working load height.
15. A railway car truck including journal boxes, coil springs upon said boxes, equalizer bars depressed between said boxes and supported at their ends upon said springs, other coil springs mounted upon said equalizer bars intermediate their ends, and a truck frame supported upon said last mentioned springs, the outer coils of said springs being severally greater in diameter than their respective working load height.
16. A railway car truck including journal boxes, coil springs upon said boxes, equalizer bars depressed between said boxes and supported at their ends upon said springs, other coil springs pivotally mounted upon said equalizer bars intermediate their ends, and a truck frame supported upon said last mentioned springs, the outer coils of said springs being severally greater in diameter than their respective working load height.
17. A railway car truck including journal boxes, coil springs upon said boxes, equalizer bars supported at their ends upon said springs, other coil springs upon said equalizer bars, and a truck frame supported upon said last noted springs, the outer coils of all of said springs being severally of greater diameter than their respective working load height.
- In witness whereof I have hereto set my hand this 30th day of June, 1926.

WILLIAM H. MUSSEY.
